UNITED STATES PATENT OFFICE.

JOHN T. S. BROWN, JR., OF PROSPECT, AND LEON L. MILES, OF LOUISVILLE, KENTUCKY.

MECHANICAL MOVEMENT.

1,265,041.

Specification of Letters Patent.

Patented May 7, 1913.

Application filed December 24, 1917. Serial No. 208,633.

To all whom it may concern:

Be it known that we, JOHN T. S. BROWN, Jr., and LEON L. MILES, citizens of the United States, and residents, respectively, of 5 Prospect and of the city of Louisville, both in the county of Jefferson and State of Kentucky, have invented a new and useful Mechanical Movement, of which the following is a specification.

10 This invention relates to mechanical movements of that class in which a rotary driving member transmits rectilinear movement to a driven member, and is designed to be used in connection with a deep well pump, 15 although it may be found of service in other branches of service.

Deep well pumps are operated with a long slow stroke, the pump rod being connected by means of a pitman rod to a crank shaft, 20 or to a wrist pin on a pulley which are driven by any suitable means. In such cases the length of the crank, or the distance of the pin from the center of the wheel is half that of the pump stroke. As the angle of 25 transmission varies continuously this method occasions considerable loss of power.

An object of this invention is to provide 30 means of the character described wherein the angle of transmission between the driving and driven members will be constant and in which the point of contact between the two members will be a minimum distance from the center of the rotary member.

Another object of the invention is to provide 35 a device by means of which strokes of any length may be obtained without increasing the amount of power supplied, and in which the rectilinear movement will be steady and positive at all times.

40 A further object is to provide a device as characterized, which will be economical in construction, durable in service and efficient in operation.

With the foregoing and other objects in 45 view, the invention consists of the novel construction and arrangement of parts illustrated in the accompanying drawings, which form a part of this specification, wherein is set forth an embodiment of the invention, 50 but it is to be understood that such changes and modifications may be resorted to as come within the scope of the claims appended hereunto.

In the accompanying drawings, comprising 55 two sheets, wherein similar reference characters designate like parts in the sev-

eral views, Figure 1, is a front elevation of an embodiment of the invention, showing the position of various parts at the completion of a down stroke, a portion being 60 broken away to show the position of the transmitting element: Fig. 2, a side elevation, a guide rod, and a brace being broken away to give a clearer view: Fig. 3, a rear elevation of the upper portion, showing the 65 position at the completion of an up stroke: Fig. 4, a central transverse section through the transmission: Fig. 5, a plan view, of the bridge plate: Fig. 6, a perspective view of the disk.

In developing our invention we employ vertical standards, or guide rods —10 and 11— erected on a base plate —12—, suitably braced by struts or props —13, 14—, and connected at the top by a cross piece —15—. 70 Cross heads —16, 17— slidably positioned on the guide rods are connected by a plate —18— of a length corresponding to the stroke to be obtained. A pump rod —19— may be connected to and extended from the 75 lower cross-head. Secured in the plate and extending laterally therefrom are a plurality of pins —20— spaced apart in vertical alinement. The outer ends of these pins are inserted in a strip —21— by which 80 they are supported and whereby they are braced. A bridge-plate —22— secured to the guide rods at a suitable point intermediate their length on what may be termed the rear side, is provided centrally with a 85 circular opening —23—. A disk —24—, slightly larger in diameter than the opening 23, is positioned concentrically thereover and is retained in that position in such a manner as to be freely rotatable about its 90 axis. The retaining means may be any suitable to the circumstances. As illustrated, said means comprises an annular ring —25— which has an exterior flange —26— adapted 95 to lie on the bridge-plate, to which it is secured by screws, and an internal flange —27— adapted to overlie the outer surface of the disk, lying in a rabbet —28— therein. The disk is provided with a central bore —29— and with another bore —30— at a 100 spaced distance therefrom. A stub shaft —31— secured in the central bore, of the disk and extending outward therefrom, bears a driving pinion —32— to which suitable means, such as a pulley —33— is 105 secured, by means of which, movement may be imparted from a suitable source of power.

A second, or intermediate shaft —34— rotatably mounted in the bore 30 and extended on both sides of the disk, carries on its outer end an intermediate pinion —35— which meshes with the driving pinion 32. On the inner end of the intermediate shaft is a sprocket wheel —36—, which is engaged with the pins 20 on the plate 18. As the sprocket wheel is rotated it causes the plate 10 and its associated parts, the cross heads and pump rod, to move longitudinally, in alternate directions, as the sprocket wheel engages with the respective sides of the pins. The pitch line of the sprocket wheel coincides with the axial line of the disk. The axis of the terminal pins, when the plate 18 is at the limit of its movement in either direction, coincides with the axis of the disk. The arrangement is such that when the 15 sprocket engages with a terminal pin it will cause the disk, which at other times is stationary, to turn through a half revolution carrying the sprocket with it so that it engages with the opposite side of the row of pins. It will be observed that the distance 20 between the center of the shaft 34 and the point where the power is applied *i. e.* the centers of the pins, does not vary as is the case with a pitman connection, consequently 25 power is transmitted with greater efficiency and there is a considerable saving in power by the use of our improved device.

It is thought that the construction and operation of our invention may be readily understood from the foregoing description, and we claim:

1. A mechanical movement comprising a reciprocable driven element, a rotatable disk mounted in a plane parallel therewith and 40 adapted to be advanced intermittently in a continuous direction, a driving pinion mounted co-axially of said disk, and an intermediate member having operative connection with said pinion and said element.

45 2. A mechanical movement comprising a reciprocable driven member, a rotatable element, a driving member mounted co-axially of and rotatable independently of said element, an intermediate member rotatably mounted on said element eccentric thereof, said intermediate member being operatively engaged with said driving and driven members, and having means for intermittently turning the rotatable element in a continuous 50 direction to shift the position of said intermediate member relative to the member with which it is engaged.

3. A mechanical movement comprising a reciprocable driven member; a rotatable element, a driving member mounted co-axially of said element, an intermediate member 60 rotatably mounted in said element and movable therewith, said intermediate member operatively engaged with both said driving 65 and driven members.

4. A mechanical movement comprising a reciprocable driven member, a rotatable element, a driving member mounted co-axially of said element and rotatable independently thereof, an intermediate member carried by 70 said element, said intermediate member being operatively engaged with the driving and driven members, and having means for changing the point of engagement with the driven member. 75

5. In a device as characterized, a reciprocable driven member, a stationary member, a disk rotatable on said stationary member, a rotatable driving member mounted co-axially of said disk, a shaft mounted in said 80 disk and extended on each side thereof, a pinion on one end of said shaft engaged with said driving member, and means on the other end of the shaft engaged with the driven member. 85

6. In a device as characterized, a plate having an opening therethrough, a rotatable member positioned over said opening, a pinion mounted co-axially of said member and rotatable independently thereof, a rotatable 90 shaft extended through the member, a pinion on each end of said shaft one of which is engaged with the first mentioned pinion. 95

7. A plate having an opening therethrough, a rotatable disk peripherally mounted over said opening, a driving pinion mounted co-axially of said disk and rotatable independently thereof, a shaft rotatably mounted in said disk and extended on each side thereof and a pinion thereon meshing 100 with the driving pinion. 105

8. A plate having an opening therethrough, an element having rectilinear movement in a plane parallel with face of said plate on one side thereof, a rotatable member mounted on the other side of the plate covering said opening, a pinion mounted co-axially of said member and rotatable independently thereof, a shaft carried by said member and extended on each side thereof 110 and means on each end of said shaft engaged respectively with said pinion and said element.

9. In a movement as characterized, a plate having an opening, a peripherally held rotatable disk covering said opening, a pinion mounted co-axially of said disk and rotatable independently thereof, a shaft carried by said disk and extended on both sides thereof, a plate adapted to be reciprocated in a plane transverse to and intercepting the axis of the disk, a plurality of engaging points on said plate, and means secured on the respective ends of said shaft and engaged respectively with said pinion and said 115 points. 120

10. A base, guide rods erected thereon, spaced cross heads slidably mounted thereon, a plate secured to said cross heads, a plurality of longitudinally aligned spaced 125 130

pins extended laterally from said plate, a bridge plate having a central opening secured to said guide rods, intermediate their length, a disk positioned on said bridge plate over said opening and rotatably held thereon by peripherally engaging means, a pinion mounted co-axially of said disk, means for rotating said pinion, a shaft car-

ried by the disk and extended from both sides thereof, a pinion on said shaft meshed 10 with the first mentioned pinion, and a sprocket wheel thereon in operative engagement with said pins.

JOHN T. S. BROWN, JR.
LEON L. MILES.
